UNITED STATES PATENT OFFICE.

ANDREW McTERNEN, OF ANDOVER, MASSACHUSETTS.

RETAINING DEVICE FOR BOTTLE-STOPPERS.

SPECIFICATION forming part of Letters Patent No. 778,203, dated December 20, 1904.

Application filed September 1, 1904. Serial No. 222,917.

To all whom it may concern:

Be it known that I, ANDREW McTERNEN, of Andover, county of Essex, State of Massachusetts, have invented an Improvement in Retaining Devices for Bottle-Stoppers, of which the following description, in connection with the accompanying drawings, is a specification, like characters on the drawings representing like parts.

10 This invention has for its object to construct a self-adjusting retaining device for bottle-stoppers especially adapted for use on bottles fitted with the ordinary cork or rubber stopper, said device being so constructed that it may be applied to bottles of different sizes having stoppers projecting different distances from its neck and when applied may be easily operated to engage and disengage the stopper.

15 My invention is embodied in a retaining device consisting of an elastic ring adapted to embrace the neck of the bottle and an elastic loop formed integral with said ring, having a cylindrical stopper-engaging portion at the end.

20 Figure 1 shows in front elevation a portion of a bottle having a retaining device for the stopper embodying this invention. Fig. 2 is a side elevation of the bottle shown in Fig. 1 and the stopper-retaining device. Fig. 3 is a

25 view similar to Fig. 2, the stopper-engaging loop being moved out of engagement with the stopper. Fig. 4 is a front elevation and partial section of the stopper-retaining device removed from the bottle. Fig. 5 is a plan view 30 of the stopper-retaining device removed from the bottle. Fig. 6 is a vertical section of the stopper-retaining device, taken on the dotted line 6 6, Fig. 4.

35 The stopper-retaining device consists of an elastic ring a and an elastic loop formed integral therewith. The ring a will be made as a flat band of any suitable size and thickness, adapted to be sprung over the usual enlargement a' at the extremity of the bottle-neck a'' , 40 so as to embrace said neck just beneath said

enlargement, and being flat will hold thereon snugly and will be prevented from easily drawing or pulling off, by engaging the enlargement on the bottle. The elastic loop which is formed integral with said ring a has 50 flat side portions $b b$ and a cylindrical end portion b' , and when in use said cylindrical end portion is adapted to be brought into engagement with the stopper c , as shown in Figs. 1 and 2, when the device is fitted onto the neck 55 of the bottle. The elastic loop may be turned down while the ring remains on the neck of the bottle, as shown in Fig. 2, for the purpose of withdrawing the stopper, after which said loop may be restored, and these operations 60 are greatly facilitated by providing the cylindrical end portion b' . When the cylindrical end portion is in engagement with the stopper, it will flatten slightly, by reason of being made of elastic material; but notwithstanding 65 such flattening it may be rolled off of or onto the stopper easily, whereas if made as a flat band great difficulty is experienced in thus manipulating the device.

70 By making both ring and loop of elastic material—as rubber, for instance—the device may be readily applied to bottles of different sizes having stoppers projecting at different distances from the neck.

75 Having thus described my invention, what I claim as new, and desire to secure by Letters Patent, is—

A retaining device for bottle-stoppers consisting of an elastic neck-embracing ring having an integrally-formed elastic loop having 80 a cylindrical end portion adapted to engage the stopper, substantially as described.

In testimony whereof I have signed my name to this specification in the presence of two subscribing witnesses.

ANDREW McTERNEN.
